KNITTED FABRIC AND METHOD

Oscar Fregeolle and Isaac H. C. Green, Central Falls, R. I., assignors to Hemphill Company, Central Falls, R. I., a corporation of Massachusetts

Application August 21, 1940, Serial No. 353,548

12 Claims. (Cl. 66—172)

This case involves an invention in elastic knitted fabrics such as are employed for garter tops of stockings or other hosiery. More specifically, the invention deals with certain improvements at the selvage of such a fabric and has for its general purpose the knitting of a selvage resistant against curling or rolling, a construction which may be easily produced on a knitting machine, and a fabric pleasing in appearance.

In the figures of drawings:

Fig. 1 is a conventional illustration of a section of fabric knitted according to one form of the invention, the same being shown greatly enlarged;

Fig. 2 is a similar showing of the fabric of Fig. 1, but illustrating to some extent the manner in which the fabric appears after the elastic yarn has contracted;

Figs. 3 and 4 show modifications wherein the method employed is slightly different, although the same general principles apply;

Fig. 5 is a conventional showing of a half hose to which the invention has been applied, the top being illustrative of the form of the invention of Figs. 1 and 2;

Fig. 6 is a similar view showing a stocking top and a portion of the leg of the stocking, the edge being knitted as in Fig. 3; and

Fig. 7 is a view similar to Fig. 6 but showing an edge knitted in accordance with the method shown in Fig. 4.

The different edges herein illustrated and described have elastic yarn incorporated in spaced wales in such a manner as to draw said wales together to simulate a rib appearance and also to impart elasticity to the fabric so that the same may serve for self-supporting purposes, one such example being that of a garter top for hosiery. Normally selvages are started with elastic being introduced at every other wale, but herein the elastic is preferably fed at every fourth wale at the very edge of the fabric and throughout the selvage portion. After that the elastic may continue to be fed at the same interval or may be introduced according to some other scheme. To obtain a selvage resistant against ravelling, non-elastic yarn is knitted in the same wales in which the elastic is introduced, and in addition, at intermediate wales. This knitting in the intermediate wales may be accompanied by tucking, or may be delayed until the entire selvage portion has been completed. In another form the intermediate wales may be so knitted as to have the

elastic incorporated therein after the initial course of non-elastic yarn.

The invention herein described results in a fabric wherein the edge portion is less bulky, although that characteristic is not displayed except by a drawing in at the edge of the fabric, this being in contrast to a flaring outwardly especially in the event the stocking or other article might be knitted in a rather coarse gage. The same applies if heavier yarns than usual are used for any particular gage.

Referring to Fig. 1, an elastic yarn 1, either covered or uncovered, is first fed to the hooks of needles at every fourth wale such as the wales 5, 2, 3 and 4. This elastic yarn may be fed at one revolution and at one feed only of a circular type, independent needle knitting machine, or may be fed two or more times. Such yarn is shown as having been introduced to the hooks of these needles twice thereby loading up what is generally known as two courses of elastic. Thereafter a non-elastic yarn 5 is fed to the hooks of needles knitting in every fourth wale and the previously held elastic yarn is cast off. According to the form of the invention being described with respect to Figs. 1 and 2, this yarn 5 is also knitted in the wales 6, 7, etc. These we shall refer to as the intermediate wales. The elastic, however, is not taken by other than needles knitting the wales 2, 3, 4, etc.

At the wales 8, 9, 10 and 11, yarn 5 is also taken in the hooks of needles knitting thereat, but throughout the so-called selvage or edge portion of the fabric these needles are to tuck so that an accumulation of loops is to be knitted in the wales 8-11. After the initial course, the elastic yarn 1 is to be cleared below needle latches so that it will be incorporated by what is generally termed inlaying in contrast to knitting. The yarn 1 is taken by needles knitting at every 4th wale and must be either taken below needle latches initially or placed below those latches before the non-elastic yarn 5 is taken whereupon as the latter yarn is drawn, the elastic will be cast off in to the fabric to be held although the same does not assume the characteristics of a knitted stitch. This inlaying is generally known at this time and need not be described further at this point.

Continuing, the yarn 5 is knitted at each course for several courses at every fourth wale while the elastic is inlaid at those wales. At the intermediate wales such as 6 and 7, the non-elastic yarn is also knitted, however, the elastic merely floats behind all needles intermediate those knitting in

wales 2, 3, 4, etc. Tucking is simultaneously done by accumulating loops in the hooks of needles knitting in wales 8, 9, 10, 11, etc. Obviously, as much of this type of elastic yarn will be taken as will serve most effectively in the production of a substantially curl resistant edge. Four courses are shown herein although fewer or more might serve better under other circumstances.

Eventually when enough of this type of fabric has been knitted, a course such as the course designated at 12 is to be knitted from the yarn 5, this yarn knitting on all needles so that all previously held loops are cast off. Of course, the wales 2, 3, 4 appear as continuous wales having elastic yarn held therein. Wales such as 6 and 7 really are unsupported and may have their yarn robbed to a certain extent and will tend more or less to roll up or knot. An attempt has been made to illustrate this at the appropriate points in Fig. 2. This Fig. 2 shows the fabric somewhat as it appears when the elastic yarn has contracted as it will when released from the needles since it is originally fed under a certain amount of tension. This tension is preferably rather light, although tension may be applied in different degrees depending upon the elastic yarn used, the ultimate elasticity desired and other details all of which contribute to the appearance and characteristics of the finished article. However, for purposes of illustration, this Fig. 2 is shown still much more open than it would be if the same were to show the fabric as it actually appears under these conditions.

After the course 12 the fabric might be knitted in one of several different ways. For example, the elastic may be knitted or otherwise incorporated in consecutive courses or spaced courses. Again, it may be held at every fourth wale as in the initial portion or may be held at every second or wales spaced at other intervals. The inlaying may continue or the elastic yarn may be knitted in conjunction with the non-elastic yarn or alone, that is, more or less as in St. Pierre Patent #2,131,720.

As herein illustrated the elastic continues to be inlaid at every fourth wale, but at every other course. This is a preferred form and is shown merely by way of illustration.

Referring to Fig. 3, a modified form of the invention is shown wherein the intermediate needles, so called, do not knit. Elastic yarn is fed at every fourth wale throughout the initial or selvage portion of the fabric and the intermediate needles, three in number, tuck. First an elastic yarn 13 is fed just as the yarn 1 was introduced in the form of the fabric of Figs. 1 and 2. This yarn is taken in the hooks of every fourth needle for two courses, more or less, and thereafter a non-elastic yarn 14 is fed to knit at the same needles. Thus the wales 15 and 16 are knitted as the wales 2, 3 and 4 were according to the preceding description. The elastic yarn is also introduced at each course for a plurality of courses and is inlaid by feeding to the hooks of these needles knitting wales 15, 16, etc., and thereafter passing said yarn below needle latches before the yarn 14 is taken. In the wales 17, 18 and 19 knitted on the three needles intermediate those in wales 15 and 16, the yarn 14 is tucked by feeding to the hooks of all three needles but not clearing latches on each of the courses constituting the selvage portion of the fabric. Throughout the courses 20, 21, 22 and 23, these stitches are held and are not cleared

and cast off until the course 24 is knitted, this being a course of non-elastic yarn knitted on all needles and corresponding to the course 12, Figs. 1 and 2.

Obviously, what has been said with respect to the first form of the invention applies here with regard to the number of courses which may constitute the anti-curl or selvage part of the fabric. Four courses of non-elastic yarn with the initial and following courses of elastic inlaid are shown for purposes of illustration and, generally speaking, a fabric knitted in that way would serve quite satisfactorily. More or fewer courses may be produced under certain circumstances.

After the course 24 is knitted, the following elastic fabric may be knitted in the manner described with respect to the preceding form of the invention disclosed.

In Fig. 4 still another modification is shown wherein the elastic is fed at each course and inlaid at every fourth needle along with a non-elastic yarn all as in the preceding forms, but in addition, the intermediate needles corresponding to those needles knitting in wales 6 and 7, Fig. 1, knit the non-elastic yarn and in addition, inlay the elastic yarn. The remaining needles tuck.

Elastic yarn 25 is introduced in the initial course as previously described and non-elastic yarn 26 knits in wales 27 and 28. In following courses the yarn 25 is inlaid at these wales. In the wale 29 the yarn 26 is also knitted; at first, however, the elastic is held only at the wales 27, 28. In wales such as 30 and 31 yarn 26 is tucked. It will be noted that this form of the invention is very much like that of Figs. 1 and 2 except for the following feature. After the initial course of elastic is cast off, the yarn 25 is fed to be inlaid at every other needle. Thus, in courses 32, 33, 34 and 35, the elastic yarn is inlaid in the wales 27, 28 and 29. After a requisite number of courses have been knitted to build up a desirable length of selvage, a course 36 knitted on all needles and from non-elastic yarn, terminates the selvage as the held loops are cleared and cast off as elongated tuck stitches.

Similarly, this type of fabric may be varied as to length of selvage and as to type and details of fabric knitted in continuation of the selvage.

Preferably, although not necessarily, these fabrics are to be knitted on a circular, independent needle knitting machine having at least one feed at which non-elastic yarns are fed and a preceding feed at which an elastic yarn is to be introduced. Needles are to be selectively controlled and yarns so manipulated that spaced needles may take the elastic, and by varying the feed of the same, it may be introduced at every course or at spaced courses. Likewise, at the non-elastic yarn feeding station certain selectivity is provided so as either to knit or tuck on such needles as are required to produce the fabric above described, these machine details and the operation of the machine in accordance therewith being understandable and capable of being carried out by those skilled in the art. While the fabric may be produced on what is generally termed a single feed machine, multifeed types may be employed if desired.

Referring to Fig. 5 a stocking is shown having a leg 37, foot 38, toe 39 and heel 40. A top 41 knitted in accordance with the method of Figs. 1 and 2 has a selvage portion 42 which appears somewhat as shown. Normally the selvage portion may be of slightly less diameter than the

top portion 41 in which event the edge is drawn in to a certain extent. Due to the fact that elastic is widely spaced at the points at which it is held in the selvage and the non-elastic yarn is tucked at every other wale and either very loosely connected to the elastic or not connected to the elastic at all at intermediate wales, this part of the fabric is allowed to contract to a greater extent or will have less bulk than following portions. This is especially true wherein the elastic is introduced at every course for several courses at the edge.

In Fig. 6 a top 43 has an edge 44 knitted in accordance with the modification of Fig. 3. This is probably the simplest form of all.

In Fig. 7 a top 45 has an edge 46 which is like that modification described with respect to Fig. 4.

Certain variations may be apparent to those skilled in the art and are intended to be included within the present disclosure and covered in the following claims. The invention as specifically described herein is merely illustrative and is not to be considered as limiting thereon. What is considered to be novel is set forth in the following claims.

We claim:

1. A selvage for a knitted fabric having non-elastic yarn and elastic yarn in combination, said non-elastic yarn being knitted in non-adjacent wales for a plurality of courses and tucked at courses intermediate those non-adjacent wales, the said elastic yarn being incorporated to be held at some only of said non-adjacent wales in which the non-elastic yarn is knitted.

2. A selvage for a knitted fabric having an elastic yarn incorporated to be held at spaced wales in which non-elastic yarn is knitted, said elastic yarn being inlaid at every fourth wale while the non-elastic yarn is knitted at alternate wales, the said non-elastic yarn also being tucked at wales intermediate those in which it is knitted.

3. A selvage for a knitted fabric having in combination elastic and non-elastic yarns, the non-elastic yarn being knitted at every fourth wale and being tucked at at least some of the wales intermediate said fourth wales, the elastic yarn being inlaid to be held at the said fourth wales only in the initial course and constituting the only yarn preventing raveling of the fabric.

4. In a knitted fabric selvage the combination of elastic and non-elastic yarns, the non-elastic yarn being knitted at non-adjacent wales and tucked at intermediate wales while the elastic yarn is inlaid at some only of the wales in which the non-elastic yarn is knitted.

5. A knitted fabric having in combination elastic and non-elastic yarns, the non-elastic yarn being knitted at every fourth wale for a plurality of courses and being tucked over said plurality of courses in all wales intermediate said fourth wales, the elastic yarn being so incorporated as to be held at said fourth wales only.

6. A knitted fabric having a selvage with elastic and non-elastic yarns incorporated therein, said non-elastic yarn being knitted at every course at recurrent wales spaced apart by more than a single wale, the said yarn being tucked at all wales intermediate the wales in which it is knitted and the elastic yarn being inlaid to be held at said knitted wales only.

7. A knitted fabric having a selvage formed from non-elastic and elastic yarns, the said non-elastic yarn being knitted at alternate wales and tucked at intermediate wales, the elastic yarn 5 passing through sinker loops at each initial stitch in every fourth wale and in following courses, said elastic yarn being inlaid to be held at stitches at alternate wales.

8. A method of knitting to form a selvage including the steps of feeding and knitting a non-elastic yarn throughout a plurality of courses and at each fourth wale in said courses, incorporating an elastic yarn in the initial stitches of said fourth wales to be held at each sinker loop therein, knitting said non-elastic yarn at wales intermediate said fourth wales and tucking that yarn at the remaining wales.

9. A method of knitting to form a selvage including the steps of feeding and knitting a non-elastic yarn at every fourth wale, tucking said 20 yarn at the three intermediate wales and over a plurality of courses, and incorporating an elastic yarn to be held in the initial stitches at said fourth wales and to be inlaid at each succeeding stitch in those wales throughout said plurality of courses.

10. A method of knitting to form a selvage including the steps of feeding and knitting a non-elastic yarn throughout a plurality of 30 courses and at each fourth wale in said courses, incorporating an elastic yarn to be held at single wales of each initial stitch in said fourth wales. knitting said non-elastic yarn at wales intermediate said fourth wales but tucking at those wales 35 between said fourth wales and intermediate wales and inlaying the elastic yarn to be held at said fourth wales and also at said intermediate wales in those courses following the said initial elastic yarn course.

11. A selvage for a knitted fabric having in combination elastic and non-elastic yarns, the non-elastic yarns being drawn into knitted 40 stitches at every fourth wale and being tucked in at least some of the wales intermediate those fourth wales, the initial loops of the fabric at each fourth wale only having the elastic yarn 45 threaded therethrough to prevent raveling, there being no other yarn in these initial loops so that the fabric is drawn together at the edge but is free to be extended to the limit of stretch in the elastic yarn itself, the said elastic yarn being further held at stitches in the said fourth wales and in following courses of the fabric.

12. A method of knitting to form a selvage including the steps of knitting non-elastic yarn at 50 spaced wales, tucking that yarn at a plurality of wales intermediate those spaced wales and preventing raveling of the fabric by incorporating an elastic yarn to be threaded through the initial 55 loops of each fourth wale only and in such a manner that said elastic yarn constitutes the only connecting yarn between those said wales in the initial course and thereafter incorporating the said elastic yarn to be held at each fourth wale at least and in stitches therein throughout 60 several courses following the initial course.

OSCAR FREGEOLLE.
